(57) **CLAIM**

The ornamental design for a position lamp for motorcycles, as shown and described.

DESCRIPTION

FIG. 1 is a front elevational view of a position lamp for motorcycles showing my new design;

FIG. 2 is a left side elevational view thereof;

FIG. 3 is a right side elevational view thereof;

FIG. 4 is a top plan view thereof;

FIG. 5 is a front left perspective view thereof;

FIG. 6 is an enlarged elevation view of FIG. 1;

FIG. 7 is an enlarged elevation view of FIG. 2;

FIG. 8 is an enlarged elevation view of FIG. 3;

FIG. 9 is an enlarged elevation view of FIG. 5; and,

FIG. 10 is an enlarged elevation view of FIG. 4.

The broken lines in FIGS. 1 through 10 illustrate environmental subject matter and form no part of the claimed design.
